CLAIM

The ornamental design for a tool handle, as shown and described.

DESCRIPTION

FIG. 1 is a rear and right side pictorial view of the tool handle;

FIG. 2 is a left elevation view of the tool handle;

FIG. 3 is a top plan view of the tool handle;

FIG. 4 is a bottom plan view of the tool handle;

FIG. 5 is a front elevation view of the tool handle; and,

FIG. 6 is a rear elevation view of the tool handle.

The broken line depiction of a tool in FIGS. 1, 2, 5 and 6 is for illustration purposes only and forms no part of the claimed design.
